(57) **CLAIM**

The ornamental design for an ice pop maker, as shown and described.

DESCRIPTION

FIG. 1 is a top perspective view of an ice pop maker showing our new design.

FIG. 2 is a bottom perspective view thereof.

FIG. 3 is a top plan view thereof.

FIG. 4 is a bottom plan view thereof.

FIG. 5 is a right side view thereof, the left side view being a mirror image thereof.

FIG. 6 is a front view thereof, the rear view being a mirror image thereof.

FIG. 7 is an exploded top perspective view thereof with an associated mold being removed therefrom.

FIG. 8 is a left side view of FIG. 7.

FIG. 9 is a right side view of FIG. 7.

FIG. 10 is a front view of FIG. 7.

FIG. 11 is a rear view of FIG. 7.

FIG. 12 is a top perspective view thereof showing ice pop sticks inserted therein.

FIG. 13 is a top plan view of FIG. 12.

FIG. 14 is a right side view of FIG. 12, the left side view being identical.

FIG. 15 is a front view of FIG. 12, the rear view being identical.

FIG. 16 is a exploded top perspective view of FIG. 12, showing one of the sticks and associated molds being removed therefrom.

FIG. 17 is a left side view of FIG. 16.

FIG. 18 is a right side view of FIG. 16.

FIG. 19 is a front view of FIG. 16.

FIG. 20 is a rear view of FIG. 16; and,

FIG. 21 is an exploded top perspective view of FIG. 12, showing the associated molds and sticks removed therefrom. The ice pop maker in FIGS. 1-11 is shown without the sticks for ease of illustration.
